UNITED STATES PATENT OFFICE.

CLAUDE A. LEWIS, OF HOUSTON, TEXAS, ASSIGNOR TO AMERICAN WINDOW COMPANY,
A CORPORATION OF DELAWARE.

WINDOW.

Application filed June 10, 1926. Serial No. 115,141.

This invention relates to new and useful improvements in a window.

One object of the invention is to provide a window, including a casing and sashes mounted on the casing in such a manner that the sashes may be readily removed or reversed so that they may be readily cleaned on both sides, from the inside of the room, and this without interfering with the window screen which may be permanently secured, if desired, to the outside of the window casing.

Another object of the invention is to provide a window of the character described, whose lower sash is vertically slidable in the usual way to provide for ventilation at the bottom of the window and whose upper sash is pivoted in the casing, at its lower end, and whose upper end may be swung inwardly and locked in open position to provide for ventilation through the upper part of the window.

A further feature of the invention resides in the provision of novel means for locking the sashes in closed position.

A still further feature of the invention resides in the provision of means for preventing the rattling of the sashes as well as means for forming water proof joints between the sashes as well as between the casing and sashes.

The invention also comprehends a novel construction of the sashes and casing whereby the sashes may be readily mounted in, or removed from the casing.

Finally, an object of the invention is to provide a window of the character described, which is of very simple construction, may be cheaply and easily installed and which is very efficient in use.

With the above and other objects in view this invention has particular relation to certain novel features of construction, operation and arrangement of parts, an example of which is given in this specification and illustrated in the accompanying drawings, wherein:

Figure 1 shows a vertical sectional view of the window frame with the sashes removed.

Figure 2 is a vertical sectional view showing the lower sash in released position for reversal, in full lines, and reversed position, in dotted lines.

Figure 3 shows a vertical sectional view with the upper sash in open position for top

ventilation, in full lines, and in reversed position in dotted lines.

Figure 4 shows a fragmentary cross sectional view, taken on the line 4—4 of Figure 1.

Figure 5 shows a fragmentary cross sectional view, taken on the line 5—5 of Figure 1.

Figure 6 shows a perspective view of a slideable anchor or guide block employed.

Figure 7 shows an enlarged fragmentary vertical sectional view of the casing head and the abutting part of the upper sash.

Figure 8 shows the abutting parts of the two sashes in section.

Figure 9 is an enlarged fragmentary vertical sectional view showing the casing sill and the abutting part of the lower sash.

Figure 10 shows an enlarged fragmentary transverse sectional view, also taken on the line 4—4 of Figure 1.

Figure 11 shows a front elevation of the complete window.

Figure 12 shows an edge view of the keeper plate of the upper sash lock.

Figure 13 shows a plan view thereof.

Figure 14 shows an end view of the upper sash lock bolt.

Figure 15 shows a plan view of the bolt bearing plate.

Figure 16 shows a side view of said bolt, as mounted in its housing, said housing being shown in section.

Figure 17 shows a sectional view of said bearing plate, taken on the line 17—17 of Figure 15.

Figure 18 shows a front elevation of the lower sash lock.

Figure 19 shows a sectional view thereof taken on the line 19—19 of Figure 18.

Figure 20 shows a cross sectional view thereof taken on the line 20—20 of Figure 19.

Figure 21 shows a front elevation of said lock casing.

Figure 22 shows an elevation of the keeper plate of the lower sash lock, and

Figure 23 shows a sectional view thereof, taken on the line 23—23 of Figure 22.

Referring now more particularly to the drawings wherein like numerals of reference designate similar parts in each of the figures the numerals 1, 1, designate the jambs of the casing, as a whole, each casing having

the head 2, and the sill 3. Each sill includes the outwardly declining ledge 4 and the inside stool 5 behind which the lower end of the lower sash 6 is adapted to fit 5 when said sash is closed.

The inner face of each jamb has a groove 7 in which the anchor blocks, as 8 are adapted to slide. The usual sash cords, as 9 are employed for the lower sash, only. The lower 10 ends of the cords are inserted into the sockets 10 of the anchor blocks and are clamped therein by means of suitable clamp screws 11 to be screwed into the counter sunk holes 12 of said blocks. These cords work over 15 the usual pulleys 13 set in the respective jambs and their other ends carry the sash balance weights 14 which are enclosed within the jambs in the usual way. There are lateral pintles 15, 15, carried by the upper 20 end of the lower sash which work in the vertical bearings 16, 16 in the inner sides of the upper ends of said blocks 8. The inner sides of said anchor blocks have long vertical bearings 17, 17, in which the lateral studs 25 18, 18, carried by the lower end of the lower sash 6, work.

Spaced above the stools 5 are the release grooves 19, 19, cut transversely across the inner faces of the blocks 8 and leading inwardly from the bearings 17. The lower sash may be elevated and lowered in the usual way through the sash lift 20 or 20' carried by said sash, the anchor blocks 8 running in the grooves 7. In order to reverse the lower 30 sash the anchor blocks 8 may be locked against movement by the barrel bolts 22 carried by the jambs 1 and the sash 6 may then be elevated until the studs 18 align with the grooves 19 and its lower end then swung outwardly, said studs passing through said 35 grooves 19 and said lower sash may then be swung around on its pintles 15 and on into the position indicated in dotted lines in Figure 2 or removed from the casing by 40 lifting until the pintles 15 disengage from the slots 15 in the block 8. If desired the lower sash, and blocks 8, may be elevated to upper position and the sash then further elevated to disengage the pintles 15 from the 45 slots 16 and the top of the lower sash, then swung inwardly on the studs 18 and this lower sash be thus reversed.

The upper sash 23 rests on the shoulders 24, 24, with its upper end fitting closely 50 against the lower edge of the head plate 25. The outer side of the upper sash frame fits closely against the marginal weather strips 26 across the top and on the inside faces of the casing.

55 In connection with the operation of the upper sash the construction of the casing should be particularly noted. The head 2 connects with the face plate at the forward part of the window casing, as in the usual form, but the outer portion of the head ex-

tends downwardly below the level of the upper wall of the casing and the plate 25 reinforces the outer member of the head. There is thus provided a wide clearance above the upper sash which, when the sash 70 is swung inwardly, permits room for ventilation, as will be now described.

Fastened to the sides of the upper sash frame at their lower ends, are the inwardly extending straps, or hook plates 27, 27, which 75 embrace the lower sash and which have the notches 28, 28, in their upper edges, forming seats which receive the pintles 15.

Fastened to the head board 24, and extending inwardly, there is a flexible keeper 80 plate 29. The upper end of the upper sash carries a spring seated bolt 30 adapted to project through a hole 31, in said plate to latch the upper sash in upright, or closed position. The ridge 29' on the under side 85 of the plate 29, and a part thereof, presses down and outwardly against the inner top-most corner of this sash, holding it firmly against the stops 26 thereby preventing 90 rattle.

If it be desired to reverse the upper sash the bolt 30 may be released from the bolt hole 31 and being held so released the upper sash may then be swung into the position indicated in dotted lines in Figure 3 so that it 95 may be easily cleaned. If it be desired to entirely remove said sash it may be lifted to disengage the notches 28 from the pintles 15 and immediately drawn inward to freedom 100 from the casing. As clearly shown in Figure 13 there is a lengthwise slot 32 in the keeper plate 29, leading from the bolt hole 31 and the projecting end of the bolt 30 has the oppositely disposed notches 33, 33, so that by giving the bolt a quarter turn 105 these notches will align with the edges of said slot and will thus release said bolt so as to permit the upper end of the upper sash to be swung inwardly till the bolt reaches the inner end of the slot 32, thus providing for 110 ventilation at the upper part of said window. The bolt 30 may be manipulated by means of the ring 34 into which its power end is formed. The projecting end of the bolt 30 works through the angular bearing plate 35 carried by the upper end of the sash 23 and said bolt is seated on a coil spring 36, all enclosed in the tubular housing 37.

The outer end of the keeper plate has a transverse slot 38, cut therethrough, and adapted to receive the sash lift of the lower sash to lock said lower sash in reversed position, as shown in Figure 2, and beyond said slot the free end of the keeper plate 22 is upwardly turned, or beveled, as at 39 so that 115 when the lower sash is reversed its lift, as 20, will strike against said upwardly turned end and elevate the keeper 29 to permit the engagement of said sash lift in the slot 38.

In order to lock the lower sash against 120

movement the barrel bolts 22 may be engaged in the bolt holes, as 40 in the anchor blocks 8.

5 A special type of sash lock has been provided and which may be used for locking the lower sash in closed position. This lock is shown in Figures 18 to 21 inclusive; it includes a casing 41, which is set into the lower end of the frame of the sash 6 and has the lateral wings 42, 42, which are fastened by 10 screws to said sash frame.

This casing 41 has a transverse bearing rod 43 whose ends are anchored to the sides of the casing and an arm 44 has its upper end pivoted on the rod 43 and its lower end is outwardly turned forming an upwardly beveled bolt 45 which works through a bearing 46 in 15 the inner side of the casing 41.

There is a release plate 47 which forms a cover for the inner side of said casing and 20 whose lower end is formed into a plunger 48, which works between the arm 44, and the opposing wall of the casing and operates against the upwardly inclined face 49 of said arm. The upper end of the plate 47 works against 25 the outer side of the bearing flange 50 at the upper end of the casing and has the inwardly extending sash lift 20' formed integrally therewith. The release plate has the inwardly extending lugs 51, 51, having the 30 oblong vertical bearings 52, 52 which work on the rod 43. A pressure spring 53 has one end anchored to the rear wall of the casing 41 with its free end pressing against the rear side of the arm 44 and normally holds the 35 bolt 45 projected through its bearing 46. A keeper plate 54 is secured to the shelf 5 and the lock bolt 45 normally engages with the keeper to lock the lower sash in closed position. If it be desired to unlock and lift said 40 sash an upward pull may be exerted on the lift 20' and this will operate, through the plunger 48, first to release the bolt 45 from its keeper, and then to elevate the sash 6, and said sash may thereby be either further elevated in the casing, or reversed or entirely removed as hereinbefore explained.

What I claim is:—

1. The combination with a window casing, of an upper and a lower sash therein, the 50 upper end of the lower sash and the lower end of the upper sash being both pivoted in the casing to revolve about a common transverse axis to permit said sashes to be swung about said axis into reversed position.

55 2. The combination with a window casing having vertical side tracks, of anchors movable in said tracks, a sash having upper and lower connections with said anchors, either of said connections being releasable to permit the sash to swing freely about a transverse axis on the other connections to permit the reversal of the sash relative to said casing.

60 3. The combination with a window casing having lengthwise side tracks, of an anchor movable in each track, a lower sash between

said anchors, each anchor and the adjacent side of said sash being provided, one with an upper and lower bearing and the other with upper and lower pintles which work in said bearings, an upper sash in said casing having 70 bearings at its lower end which work on said upper pintles.

4. The combination with a window casing having lengthwise side tracks, of an anchor movable in each track, a lower sash between 75 said anchor and the adjacent side of said sash being provided one with an upper and lower bearing and the other with upper and lower pintles which work in said bearings, an upper sash in said casing having bearings at its 80 lower end which work on said upper pintles and are releasable therefrom.

5. The combination with a window casing having lengthwise side tracks, of an anchor movable in each track, a lower sash between 85 said anchors, each anchor and the adjacent side of said sash being provided, one with an upper and lower bearing and the other with upper and lower pintles which work in said bearings, an upper sash in said casing having 90 bearings at its lower end which work on said upper pintles and means for locking said upper sash in fixed position in the casing.

6. The combination with a window casing, of a sash therein pivoted to revolve about a 95 transverse axis, a locking device adapted, in one position, to lock said sash closed and in another position to permit said sash to partially open.

7. The combination with a window casing, 100 of a sash therein pivoted to revolve about a transverse axis, a locking device adapted, in one position, to lock said sash closed and in another position to permit said sash to partially open, said locking device being releasable to permit said sash to swing about said axis into reversed position.

8. The combination with a window casing, 105 of an upper sash pivoted near its lower end to revolve in said casing on a transverse axis 110 spaced forwardly out of alignment with said sash, said sash being bodily removable from said casing.

9. The combination with a window casing, 115 of a sash therein pivoted near its upper end in the casing to revolve about a transverse axis to permit the sash to be reversed in the casing and interlocking means carried by the sash and casing respectively and adapted to hold said sash in reversed position.

10. The combination of a window casing, 120 a lower sash slideable in said casing, pintles on said lower sash adjacent its upper end, said sash being pivoted thereon, and an upper sash pivoted at its lower end to swing on 125 said pintles.

11. The combination of a window casing, a lower sash slideable in said casing, opposite pintles on said lower sash, and an upper sash pivoted at its lower end to swing on said 130

pintles when said lower sash is in its lowered position.

12. The combination of a window casing, a lower sash slidable therein, and an upper 5 sash pivoted in a vertical plane inwardly of said upper sash, to swing into reversed position in front of said lower sash.

13. The combination of a window casing, a lower sash slidable vertically therein, 10 pintles at the upper end of said lower sash, an upper sash mounted in said casing and offset outwardly of said lower sash, and plates at the lower end of said upper sash engaging said pintles, whereby said upper 15 sash may swing on said pintles.

14. In a window, a casing, an upper sash, plates on the lower end thereof projecting forwardly of the plane of said sash, the forward ends of said plates having pin engaging recesses therein and pivot pins in said 20 recesses, about which said sash may swing.

15. In a window, a casing, a lower sash mounted to slide in said casing, means upon which said sash is mounted to allow said sash 25 to swing inwardly into reversed position, an upper sash, and a pivot for said upper sash supported in the plane of said lower sash, to allow said upper sash to swing inwardly into reversed position.

16. In a window, a casing including a lower sill, side jambs and an upper head plate, said head plate having a downward extension at its outer side below the upper wall of the 30 plate; in combination with an upper sash in said casing, means to pivotally support said sash at its lower end, the upper end of the sash fitting normally against the lower end of said plate extension, whereby space is provided above said sash for ventilation when 35

said sash is swung into vented position, in 40 the manner described.

17. In a window, a casing including a lower sill, side jambs and an upper head plate, said head plate having a downward extension at its outer side below the upper wall of the 45 plate; in combination with a sash in said casing pivoted at its lower end to swing inwardly at its upper end, the upper end of said sash extending upwardly to meet the lower end of said plate extension, there being 50 a wide clearance between said sash and the upper wall of said head plate when said sash is swung inwardly.

18. In combination with a window casing having vertical side tracks, of anchors movable in said tracks, a sash between said anchors, each anchor and the adjacent sash being provided one with upper and lower bearings and the other with upper and lower sets of pintles which work in said bearings, 60 either of said pintles being adapted to act as a pivot about which said sash may swing, the pintles at the opposite end of the sash from those acting as pivots being readily detachable from engagement with their bearings to 65 allow the swinging of the sash.

19. A combination of a window casing, anchors slidable in said casing, a sash on said anchors, upper and lower pintles on said sash engaging in upper and lower grooves in said 70 anchors, both said pintles being adapted to move free of said grooves, both ends of said sash being adapted to swing inwardly with pintles at the opposite end as a pivot.

In testimony whereof I have signed my 75 name to this specification.

CLAUDE A. LEWIS.
